(57) CLAIM

The ornamental design for a bottle, as shown and described.

DESCRIPTION

FIG. 1 is a front elevational view of a bottle, showing my new design, with the bottle being symmetrical, annularly about its periphery;

FIG. 2 is a top plan view of the bottle of FIG. 1; and,
FIG. 3 is a bottom plan view of the bottle.

The broken lines in FIGS. 1 and 3 showing exemplary bottom structure of the bottle is for illustrative purposes only and forms no part of the claimed invention.
